(57) CLAIM

The ornamental design for a cosmetic container as shown and described.

DESCRIPTION

FIG. 1 is a perspective view of a cosmetic container showing a new design;

FIG. 2 is a front view thereof;

FIG. 3 is a back view thereof;

FIG. 4 is a top view thereof;

FIG. 5 is a bottom view thereof;

FIG. 6 is a left view thereof; and,

FIG. 7 is a right view thereof.

The broken lines depict portions of the cosmetic container that form no part of the claim.
